UNITED STATES PATENT OFFICE.

JACOB R. SCOTT, OF NORTH WEYMOUTH, MASSACHUSETTS, ASSIGNOR TO UNITED SHOE MACHINERY COMPANY, OF PATERSON, NEW JERSEY, A CORPORATION OF NEW JERSEY.

SHOE-SEWING MACHINE.

1,127,098.

Specification of Letters Patent.

Patented Feb. 2, 1915.

Original application filed December 5, 1907, Serial No. 405,235. Divided and this application filed January 8, 1913. Serial No. 740,764.

To all whom it may concern:

Be it known that I, JACOB R. SCOTT, a citizen of the United States, residing at North Weymouth, in the county of Norfolk 5 and Commonwealth of Massachusetts, have invented certain Improvements in Shoe-Sewing Machines, of which the following description, in connection with the accompanying drawings, is a specification, like 10 reference characters on the drawings indicating like parts in the several figures.

This invention relates to shoe sewing machines, and more particularly to shoe sewing machines in which the work is supported 15 during the sewing operation by a horn which extends within the shoe. Certain features of the invention, however, are not limited to this type of machine, but may be embodied with advantage in other shoe sewing machines.

The object of the invention is to provide shoe sewing machines with improved devices for applying wax to the thread.

With the above object in view, the invention 25 consists in the devices and combinations hereinafter described and particularly pointed out in the claims.

In the accompanying drawings illustrating 30 a portion of a shoe sewing machine embodying the novel features of the invention in their preferred forms, Figure 1 is a longitudinal sectional view of the horn of the machine; Fig. 2 is a plan view of the base of the horn; and Fig. 3 is a central cross-sectional view of the horn and its stem, illustrating particularly the construction of 35 the wax pot support in the horn and the heating appliances carried by the horn.

The machine in which the preferred form 40 of the invention is embodied has the same general construction and arrangement of parts as the well-known McKay shoe sewing machine. This machine is illustrated and described in applicant's Patent No. 45 1,050,568, granted January 14, 1913 on an application Serial No. 405,235, filed December 5, 1907, of which the present application is a division. In the present application only the work supporting horn of the 50 machine, and the devices supported on the horn, have been illustrated, inasmuch as this illustration is considered sufficient to give a clear understanding of the invention.

The horn of the machine comprises a base

portion 1 and an upwardly curved portion 55 2 of the shape commonly used to enter the shoe. From the base of the horn a stem 3 extends downwardly through a bearing in a projection 4 from the machine frame, so that the horn can be rotated, as is usual in 60 this class of machines. Preferably a ball bearing 5 is provided between the base of the horn and the upper surface of the projection from the frame of the machine through which the stem passes. Below its 65 bearing the cylindrical stem of the horn tapers slightly, and from the lower end of the tapered portion two concentric sleeves 6 and 7 extend downwardly through a stationary bushing 8. The inner sleeve 7 ex- 70 tends below the outer sleeve 6, and at its lower end is journaled in a bushing 9 mounted in a projection 10 from the machine frame.

The whirl is of the usual construction, and 75 has the usual operation. It is mounted in the tip of the horn, and is driven by a pinion on the upper end of an inclined shaft 11 in the upper end of the horn. The inclined shaft 11 is driven from a vertical 80 shaft 12 in the horn, which shaft is provided with a pinion 13 at its lower end in the base of the horn which is driven through two intermediate gears 14 from a gear 15 on a vertical shaft 16 extending through the 85 center of the stem of the horn. This shaft passes through the sleeves 6 and 7 at the lower end of the stem, and is rotated through suitable connections from the cam shaft of the machine.

The heating apparatus of the machine 90 comprises a heating chamber 17 mounted in the horn at one side of the vertical shaft 12, and a plate 18 provided with heating chambers in the base of the horn in position to 95 form a support for the wax pot to rest upon. Steam is supplied to the heating chambers as follows: Supply and exhaust pipes 19, 20 lead to the bushing 8 through which the sleeves 6 and 7 at the lower end 100 of the stem of the horn pass, and these pipes connect with passage ways leading to circular channels 21 and 22 on the inner surface of the bushing. These channels connect by means of passage ways in the inner 105 sleeve 7 to pipes 23 and 24 located on opposite sides of the stem of the horn and connected at their upper ends to the chambers

in the heating plate 18 upon which the wax pot rests. These chambers are connected by pipes 25 and 26 to the heating chambers 17 of the horn.

5 The wax pot 27 rests upon the heating plate 18 in the base of the horn, and is provided with a horizontal shelf 28 extending from its lower end upon which the thread holder 29 is supported. A clamping screw 10 30 extends upwardly through a slot 31 in the base of the horn into this shelf, and serves as a means for securing the wax pot in position. The slot permits the wax pot to be moved outwardly on the base of the horn 15 so that access can readily be had to the parts in the horn beneath the pot. Secured to the under side of the cover of the wax pot is a casting, shaped to form two vertical tubes 32 through which the thread 33 passes in entering and leaving the pot, the upper ends 20 of these tubes extending through holes in the cover of the pot. At their lower ends the tubes are connected by a shelf 34 which slopes downwardly on each side from the center and forms a roof over the thread 25 passing through the pot to prevent any unmelted lumps of wax from sinking down into contact with the thread. Below the shelf the thread passes over two guide rolls 35 30 supported in projections from the casting and through holes formed in projections 36 from the shelf, which holes act as strippers to remove lumps of wax from the thread. All the parts for guiding and supporting 35 the thread while passing through the wax pot are thus mounted upon the cover, and can be removed by taking off the cover. To enable the melted wax to be strained before it comes in contact with the thread, 40 two walls 37, provided with vertical slots, project upwardly from the bottom of the wax pot and contact with the outer edges of the shelf 34. A hinged lid 38

on the cover of the wax pot permits 45 fresh wax to be placed in the pot without removing the entire cover. As the thread passes from the wax pot it passes over a guide roll 39 and under a stripper 40 supported on the upper side of the cover between two walls 41 projecting from the 50 cover. A removable casing 42 fits over the walls 41 and incloses the stripper 40 and guide roll 39. From the guide roll 39 the thread passes downwardly around a tension wheel and then upwardly over a tension roll 55 mounted in a spring pressed arm and then over a guide roll in the horn and through the eye of the whirl.

Having explained the nature and object 60 of the invention, and having specifically described the preferred embodiment thereof, what is claimed is:—

1. A wax pot for shoe sewing machines, having, in combination, two tubes through 65 which the thread enters and leaves the pot, a shelf connecting the lower ends of the tubes and forming a roof over the thread, thread guides beneath the shelf, and perforated walls extending from the shelf to the bottom 70 of the pot on each side of the thread.

2. A wax pot for shoe sewing machines, having, in combination, two tubes through which the thread enters and leaves the pot connected at their upper ends to the cover 75 of the pot, a shelf connecting the lower ends of the tubes and forming a roof over the thread, and thread guides located beneath the shelf.

In testimony whereof, I have signed my 80 my name to this specification in the presence of two subscribing witnesses.

JACOB R. SCOTT.
